UNITED STATES PATENT OFFICE.

RICHARD SCHULZ, OF BERLIN, GERMANY.

WATER-TUBE BOILER.

SPECIFICATION forming part of Letters Patent No. 655,803, dated August 14, 1900.

Application filed October 21, 1899. Serial No. 734,358. (No model.)

To all whom it may concern:

Be it known that I, RICHARD SCHULZ, engineer, a subject of the King of Prussia, German Emperor, residing at Berlin, Germany, 5 have invented certain new and useful Improvements in Water-Tube Boilers; and I do hereby declare the following to be a full, clear, and exact description of the invention, such as will enable others skilled in the art 10 to which it appertains to make and use the same, reference being had to the accompanying drawings, and to letters of reference marked thereon, which form a part of this specification.

15 The present water-tube boiler belongs to that kind in which an upper boiler and a plurality of under boilers are connected by means of a large number of narrow water-tubes which in general open into the water-space, 20 but which may, however, open into the steam-space. The separate groups of water-tubes connecting the upper boiler with the under boiler form draft-flues by a number of tubes being placed in close proximity to one another to form partitions in a well-known manner, so that the gases of combustion have to 25 pass a long way through the flues to the chimney and enter the latter with as low a temperature as possible. These draft-flues, in 30 which are formed combustion-chambers containing no water-tubes, are arranged for this purpose in such manner that the main portion of the fire-gases passing first over the combustion material in the fireplace and entering said draft-flues has before entering the one or the other chamber already transmitted a part of its heat to the water-tubes, and some of the water-tubes are so arranged that a small portion of fresh fire-gases is allowed of 35 40 entering a combustion-chamber directly from the fireplace and, if desired, together with atmospheric air where the main portion of the fire-gases is entering the said chamber, so as to render as complete as possible the 45 combustion of such fire-gases, the combustion of which should still be incomplete.

Figure 1 of the accompanying drawings shows a section on line 1 1 of Fig. 2 of an example of a water-tube boiler; Fig. 2, partly 50 a section on line 2 2 of Fig. 1 and partly a plan view of the same. Fig. 3 shows a sec-

tion on line 3 3 of Fig. 4 of another example of a boiler; Fig. 4, partly a section on line 4 4 of Fig. 3 and partly a plan view of the same. Fig. 5 shows a section on line 5 5 of 55 Fig. 6 of another example; Fig. 6, partly a section on line 6 6 of Fig. 5 and partly a plan view of the same, and Fig. 7 shows a vertical section of a further mode of construction.

In all examples an upper boiler *a* is connected with three under boilers *b c d*. 60

In the example shown in Figs. 1 and 2 the upper boiler is connected with the under boilers in such manner that there are two groups of water-tubes which open into the upper 65 boiler *a* and the middle under boiler *c*, while but one group of such tubes is provided for connecting the two other under boilers *b* and *d* with the upper boiler *a*. Each of these groups contains water-tubes *e*, which are represented as having a greater diameter than the other tubes *f* and are placed in close proximity to one another and form the partitions between which the fire-gases pass to the chimney, thereby giving off their heat as 70 well to the partition water-tubes *e* as to the other water-tubes *f*, arranged in the respective flues, as is well known in water-tube boilers.

In the example shown in Figs. 1 and 2 80 there are formed two inner draft-flues by means of the tubes *e* connecting the boilers *a* and *c*, and two outer draft-flues by means of the tubes *e* connecting the boiler *a* with the boilers *b* and *d*, respectively. The 85 front ends of these inner and outer draft-flues are provided with combustion-chambers *h* and *h'*, respectively, as seen in Fig. 2. At this end, as indicated by the arrow *z* in Fig. 1, the arrangement of the tubes *e*, facing each 90 other, is such that open spaces are formed between them, so that a small portion of fire-gases is allowed of passing directly from the fireplaces *g* into the combustion-chambers *h'* of the two outer draft-flues. The rear end of 95 the inner draft-flues is separated from the smoke-box *k* and its chimney *l* by means of a baffle-plate, while the rear end of the outer draft-flues opens into the said smoke-box *k*. The main portion of the fire-gases passes first 100 over the combustion material in the fireplaces *g* and enters, as indicated by arrows *x*, the

inner draft-flues at their rear end, takes its course to the combustion-chambers h of the inner flues, and passes from here over into the combustion-chambers h' of the outer flues, as indicated by the arrows y , Fig. 2. The fire-gases are caused to linger as long a time as possible in these chambers, and in this condition a small portion of fresh fire-gases enters the chambers h' directly from the fire-places through the open spaces formed here toward the fire-places g between the tubes e , facing each other and indicated by the arrow z . If desired, atmospheric air may be conducted through these open spaces together with said fresh fire-gases, so as to render as complete as possible the combustion of the fire-gases before they reach the smoke-box k on their way through the two outer draft-flues. Also in the other examples the partition water-tubes are indicated by e , the water-tubes arranged in the draft-flues by f , the combustion-chambers by h and h' , respectively, and the open spaces formed between the combustion-chambers h' and the fire-places g are marked with arrows z .

In the example shown in Figs. 3 and 4 the upper boiler a is connected with the under boilers $b c d$, so that, as in Figs. 1 and 2, there are two groups of water-tubes which open into the upper boiler and the middle under boiler c , while but one group of tubes is provided for connecting the boilers b and d with the upper boiler. The middle part of each inner draft-flue is provided with a combustion-chamber h and the middle part of each outer draft-flue with a combustion-chamber h' , as seen in Fig. 4. The main portion of the fire-gases enters, as indicated by arrows x , all draft-flues at their front end and takes its course to the combustion-chambers $h h'$. Here the fire-gases are caused to linger as long a time as possible, and in this condition a small portion of fire-gases enters the combustion-chambers directly from the fire-places g , as indicated by arrow z , Fig. 3, through open spaces formed toward the fire-places between the tubes e , facing each other above the latter. If desired, atmospheric air may be conducted through said open spaces, so as to complete as much as possible the combustion of the fire-gases before their passage into the smoke-box k and chimney l .

In the example shown in Figs. 5 and 6 the fire-gases enter the inner draft-flues both at the front and rear end thereof and pass over from the combustion-chambers h , arranged at the middle of the flue, into the combustion-chambers h' of the next parallel flues, take then their course toward both ends of the latter, and pass over into the outer flues, through which they are conducted to the smoke-box k , arranged in the middle part of the boiler. Here also, as indicated by the arrow z , Fig. 5, a small portion of fire-gases enters the combustion-chambers h' directly from

the fire-places through open spaces formed between the tubes e , which face each other above the fire-places. By this small portion of the fire-gases and, if desired, aided by atmospheric air to be conducted through said open spaces the combustion of the fire-gases is completed before their passage into the outer draft-flues and the smoke-box.

In all examples before described the fire-gases take their course from the fire-places to the chimney substantially in a horizontal direction through the draft-flues.

In the example shown in Fig. 7 the arrangement of the groups of water-tubes is such that draft-flues are formed, causing the fire-gases to take their way in an upward and downward direction, as indicated by arrows $x y$, from the fire-places g to the smoke-box and chimney. Here also combustion-chambers $h h'$ are arranged, which cause the fire-gases to linger as long a time as possible therein. As indicated by the arrow z , a small portion of fresh fire-gases coming directly from the fire-places g enters the combustion-chambers h' here also through open spaces formed between the water-tubes e , facing each other above the fire-places.

It will readily be seen that the products of combustion entering the inner flues h at their rear end and flowing from their forward end into the outer flues h' to escape into the smoke-box k at the rear end of said flues h' are gradually cooled and carry with them a large proportion of unconsumed carbon; but by supplying products of combustion direct from the fire-spaces, and consequently of the highest temperature and pressure, to the flues h at their forward end, together with air, if necessary, said products of combustion entering the flues h substantially at right angles to the flow of the products of combustion therein, an intimate admixture and the combustion of unconsumed carbon results, so that the forward ends of inner and outer flues constitute, in fact, auxiliary combustion-chambers.

Having now particularly described my invention, what I claim as new, and desire to secure by Letters Patent, is—

1. A water-tube boiler having water-tubes connecting a plurality of lower boilers with an upper boiler, said water-tubes arranged to form main and return-draft flues, and means for admitting fire-gases direct from the fire-space to the main flues at or near the point where the products of combustion flow therefrom into the return-flues, substantially as and for the purpose set forth.

2. A water-tube boiler having water-tubes connecting a plurality of lower boilers with an upper boiler, a portion of said water-tubes arranged to form contiguous flues opening into each other at their forward end, means causing the products of combustion to enter one of said flues at its rear end, to escape

from the other at the like end, and openings at the forward end of the main flue placing the same in direct communication with the fire-space below the flues, said openings ar-

5 ranged to direct the fire-gases into said main flue at substantially a right angle to the direction of flow of the products of combustion, for the purpose set forth.

In testimony that I claim the foregoing as my invention I have signed my name in presence of two subscribing witnesses.

RICHARD SCHULZ.
